MINING MACHINE.

No. 374,900.

Patented Dec. 13, 1887.

N. PETERS, Photo-Lithographer, Washington, D. C.

UNITED STATES PATENT OFFICE.

BENJAMIN A. LEGG, OF COLUMBUS, OHIO, ASSIGNOR TO THE LECHNER MANUFACTURING COMPANY, OF SAME PLACE.

MINING-MACHINE.

SPECIFICATION forming part of Letters Patent No. 374,900, dated December 13, 1887.

Original application filed December 10, 1885, Serial No. 185,967. Divided and this application filed July 9, 1887. Serial No. 243,855.
(No model.)

To all whom it may concern:

Be it known that I, BENJAMIN A. LEGG, a citizen of the United States, residing at Columbus, in the county of Franklin and State of 5 Ohio, have invented certain new and useful Improvements in Mining-Machines, of which the following is a specification, reference being had therein to the accompanying drawings.

10 This invention relates to improvements in mining-machines of that class in which each has a bed, a carriage, cutting apparatus on the carriage, power mechanism at the rear of the carriage, two sets of gearing—one for advancing the carriage and the other for withdrawing it—a reversible shaft, and a sliding clutch on the shaft adapted to engage alternately with the advancing mechanism and the withdrawing mechanism.

15 Inasmuch as most of the parts which constitute the mechanism as a whole are now well known, it is not necessary to describe all of them in detail.

Reference may be had to earlier patents—such 20 as that heretofore granted to me, No. 299,655, dated June 3, 1884, wherein will be found illustrated a machine adapted to have applied to it the improvements to which this case relates; but it will be understood that the present invention is not limited to a machine all 25 of whose parts are like those in said patent, as it can be used in any of many modified types, so long as it contains those parts which are necessary to have the present features applied thereto.

Figure 1 is a top plan view of sufficient part of a mining-machine to illustrate my improvements. Fig. 2 is a perspective of some of the parts. Fig. 3 is a section of that in Fig. 2. 30 Fig. 4 is a section of that in Fig. 1, showing a shifting-lever for the clutch above the air-inlet or steam-inlet pipes of the engines, as shown in said Fig. 1. Fig. 5 is a similar section, there being here shown a lever for shifting the clutch 35 at a lower point, as in Figs. 2 and 3. Fig. 6 is a cross-section of some of the parts in Figs. 2, 3, and 5, it showing, also, the cross-braces or tie-pieces illustrated in my aforesaid patent, No. 299,655.

40 The bed-frame is indicated by A, it having

side bars and cross-bars of any suitable number and character, as shown in the aforesaid patent, and also herein at A'. The carriage is fitted to the bed and slides to and fro thereon, it having a plate, B, secured to guide-rails b. 55 This carriage carries the cutting apparatus, (not shown,) the engines, the cross-shafting communicating the power to various operative parts, and a feed and recede shaft, k, provided with wheels k', meshing with racks at a' on the stationary frame A, and through which the traveling carriage is fed forward and back in operating the machine. The power is transmitted from the cross-shafting f g to this shaft k for advancing the frame by an inclined shaft 60 at i, which turns the wheel i', running loosely on the shaft k and engaging with said shaft through the clutch m, splined to said shaft; but other means may be used instead of the inclined shaft i and the parts directly incident 65 thereto. The carriage is fed backward or withdrawn by another set or train of devices of suitable character—such, for instance, as the chain shown in my aforesaid earlier patent, or by the eccentric and ratchet therein 70 shown, or by means of another shaft, l, running backward from the cross-shafting f g. In either case the wheel l', (whether ratchet-wheel, sprocket-wheel, or worm-wheel,) running loosely on the shaft k, is actuated, which 75 wheel also can be engaged with said shaft k through the aforesaid clutch m. The speed of the feed-gearing is lower than that of the recede-gearing, of whatever sorts the said gearings may be respectively.

80 The clutch m is operated by means of the sliding rack-bar m', mounted in suitable guides and having parts at m² fitting in the annular seat m³ in the clutch m. A pinion, n, on the lower end of the vertical bar n' engages with 85 the rack-face on the bar m', the said bar n' having an arm, U², by means of which, through the pinion n and rack-bar m', the clutch m can be thrust into and out of engagement with either wheel i' or l', according to the desired 90 movement of the carriage B b. The bar or shaft n' is at the upper end held by a support, n⁴, secured to the engine part of the machine.

95 There are plates or standards C secured to the carriage and rising upward therefrom, 100

which carry the engines D and the guides E, and to any of these parts extended upwardly from the carriage the upper end of the bar or shaft n' can be connected. I prefer that the support n' should comprise a cross-bar secured to each of the engines, but it may be otherwise arranged. The air-inlet or steam-inlet pipe for the engines is indicated by F, and extends straight across from engine to engine. There may be an arm or lever, U², for operating the clutch above this air-pipe F, as shown in Figs. 1 and 4, or there may be one lower down and nearer the plane of the stationary bed, as shown in Figs. 2, 3, 5, and 6.

By interposing a supplemental mechanical movement between the vertical bar or shaft n' and the clutch m , I can attain several important ends—as, for instance, I can apply greater leverage and can arrange the shifting mechanism advantageously. While I prefer the position shown for these parts relative to the clutch, I do not wish to be limited to such position, as these parts can be otherwise placed, according as the relative positions of the other parts of the machine may demand, for the sake of convenience or the best application of the power. So, too, while I prefer to employ a rack and pinion as such movement, I do not wish to be limited thereto, as other ways of accomplishing the same end will readily suggest themselves to those acquainted with such machines.

It is now well known that the clutch-shifting devices in mining-machines may be operated automatically—that is to say, while the carriage is moving in one direction or the other upon the bed-frame, and as is illustrated in earlier patents—and the rack and pinion herein shown, or other equivalent devices, can be applied automatically in any of the well-known ways.

The sliding rack-bar m' is held by a guide, M², fitted to a supporting-plate, M³, secured

to the under side of the carriage-plate B; but I do not wish to be limited to this as a device 45 for holding the carriage-shifter in place.

I do not in this case claim any matters claimed in my earlier application, No. 185,267, filed December 10, 1885, of which earlier application the present one is a division; nor do I claim the combination, with the feed and recede shaft k and the wheels l' , of the inclined shaft i , worm-wheel i' , and the bevel-gears which drive the shaft i , nor any other part of the gearing employed for either advancing or withdrawing the cutting apparatus, reserving the right to claim such parts thereof as may be patentable in my said earlier pending applications, Serial No. 185,267, filed December 10, 1885, Serial No. 190,931, filed February 5, 60 1886, and in the joint application No. 166,299, filed May 21, 1885, by Legg and Dierdorff, preferring to make the clutch-shifting mechanism the subject-matter of the claims herein.

What I claim is—

1. In a mining-machine, the combination of the feed and recede shaft, the wheels l' i' , mounted thereon, clutch m , sliding rack-bar m' , and clutch-bar n' , carrying the pinion n , meshing with said rack, substantially as and 70 for the purposes set forth.

2. In a mining-machine, the combination, with the clutch m , keyed to the shaft k , of the sliding rack-bar m' , and clutch-bar n' , carrying the pinion n , meshing with said rack-bar and 75 carrying the operating-lever, the upper end of said bar n' being supported in the parts projecting upward from the carriage, substantially as set forth.

In testimony whereof I affix my signature in 80 presence of two witnesses.

BENJAMIN A. LEGG.
